(57) **CLAIM**

The ornamental design for a basket for a children's riding vehicle, as shown and described.

DESCRIPTION

FIG. 1 is a front perspective view of the basket for a children's riding vehicle, in an open position;

FIG. 2 is a front elevational view of the basket for a children's riding vehicle, in an open position;

FIG. 3 is a rear elevational view of the basket for a children's riding vehicle, in an open position;

FIG. 4 is a left side elevational view of the basket for a children's riding vehicle, in an open position, the right side elevational view being a mirror image thereof;

FIG. 5 is a top plan view of the basket for a children's riding vehicle, in an open position;

FIG. 6 is a bottom perspective view of the basket for a children's riding vehicle, in an open position;

FIG. 7 is a front perspective view of the basket for a children's riding vehicle, in a closed position;

FIG. 8 is a front elevational view of the basket for a children's riding vehicle, in a closed position;

FIG. 9 is a left side elevational view of the basket for a children's riding vehicle, in a closed position, the right side elevational view being a mirror image thereof;

FIG. 10 is a top plan view of the basket for a children's riding vehicle, in a closed position; and,

FIG. 11 is a bottom perspective view of the basket for a children's riding vehicle, in a closed position.

The portions shown in broken lines form no part of the claimed design.
